MOTOR, HANDLE AND MOUNTING UNIT FOR ROTATABLE BRUSHES

Ralph H. La Bossier, 27915 10th Ave. S.,
Auburn, Wash. 98002

Filed Dec. 23, 1969, Ser. No. 20,615

Term of patent 14 years

Int. Cl. D4—04

U.S. Cl. D4—38

FIG-1

FIG-2

FIG-3

FIG. 1 is a top plan view of motor, handle and mounting unit for rotatable brushes embodying my new design;

FIG. 2 is a side elevation view thereof;

FIG. 3 is a perspective view thereof;

The broken lines are for illustrative purposes only.

I claim:

The ornamental design for a motor, handle and mounting unit for rotatable brushes, substantially as shown and described.
